COMBINED CLOSURE AND DISPENSER FOR A PRESSURIZED CONTAINER

Victor Koenigsberg, Franklin Square, N.Y., assignor to
Colgate-Palmolive Company, New York, N.Y., a cor-
poration of Delaware

Filed May 17, 1963, Ser. No. 74,939

Term of patent 14 years

(Cl. D58—26)

FIG. 2

FIG. 1

FIG. 6

FIG. 7

FIG. 5

FIG. 8

FIGURE 1 is a side elevation of a combined closure and dispenser for a pressurized container wherein the top surface of the combined closure and dispenser is concave and the side wall surface thereof is striated; and

FIGURE 2 is a top plan view thereof;

FIGURE 3 is a front elevation thereof;

FIGURE 4 is a rear elevation thereof;

FIGURE 5 is a perspective view thereof;

FIGURE 6 is a top plan view of a combined closure and dispenser for a pressurized container wherein the top surface of the combined closure and dispenser is substantially flat and wherein the side wall surface of the combined closure and dispenser is plain;

FIGURE 7 is a rear elevation thereof; and

FIGURE 8 is a rear perspective view thereof.

The essential generic features of the design herein reside in the combination, in a closure, of a dispensing control member having the configuration shown and a finger engaging surface, said control member and said finger engaging surface having substantially coordinate tapers diametrically across the top of the closure, the major portion of the control member having a top surface continuous with that of the remainder of the top surface of the closure, and wherein the nozzle opening is con-

tinuous with the dispensing control member and is located in the upper third of the side wall of the closure in a substantially rectangular recessed area, all as shown.

The portions shown in broken lines are for illustrative purposes only.

I claim:

The ornamental design for a combined closure and dispenser for a pressurized container, substantially as shown and described.
